J. Van Caster.

Churn.

No

Patented July 27, 1832.

Isaac Van Gender of Warren, Ohio
Setters Boxed.

The Schedule referred to in the following Patent and making part of the same containing a description in the words of the said Isaac Van Gender himself of his improvement in the wheel or

to all to whom these presents shall come. Be it known that I, Isaac Van Gender of Warren in the County of Trumbull and State of Ohio have invented a new and useful improvement in the Butter Churn and that the following is a full and exact description of the construction and operation of the said machine as invented or improved by me to wit. The body of the churn is a square box composed of two sides, two ends, a bottom and lid. The side and end pieces are made of boards one and one fourth inch in thickness planed and nailed together at the corners. The grain of the wood in the sides running horizontally and of the ends perpendicular. The width of the sides is nine inches as the length of the ends corresponds with the width of the sides except so much of the end as extends above the body of the churn forming the posts. The bottom one inch in thickness is let into a groove made in the side and end pieces, three inches above their lower edge.

The lid consists of two pieces of equal width one inch in thickness and is let into the top of the churn resting on a shoulder.

The depth of the churn in the clear is four and one half inches the length twenty inches and the width ten inches. Two round shafts, one and one fourth inch diameter are placed in the churn in an upright position. The axis of the shafts are exactly in the centre of the churn one fourth of the length being one fourth the length of the churn in clear from each end, having one half the length of the churn in clear between them.

pins or round, feet thru the shafts fast in the darkness. The shafts play on guides, at the lower end, let into the bottom of the churn at the top ends of the shafts are guides which play in the lower edge of one of the plates which plate passing lengthways, over the centre of the churn. Three inches of the top ends of the shafts are turned two

June 27, 1832

and one fourth inches in diameter with a small projecting lip at the extreme top) forming pulleys round which the cord passes. The rings are made of an inch diameter and ten inches long. The number of pins in each shaft is six, the first pin is half an inch from the bottom. The second at right angles to the first, and one inch above it and so on alternately each crossing the one next to it at right angles, with the space of an inch between. A spit at each end of the groove for the support of the top work is formed by continuing the pieces ^{out} a distance of ten inches above the top of the lids. The posts are seven-eighths of an inch in thickness, and four and a half inches wide at the top the lower part of the post near the body of the churn may be made wider than the top or not to suit the fancy of the workman. Two plates ten and three fourths inch is wide and one inch in thickness pass over the churn length ways tied together at each end by a round or joint passing between the plates close to the middle of the posts. The top edge of the plate is taken out at each corner with a quarter circle so as to leave out four and a half inches wide at each end where it rests on the posts. A groove corresponding in width to the thickness of the post and three eighths of an inch deep is made in each end of each plate where it comes against the post and each edge of the posts at the top end is cut off in eighths of an inch wide as low down as the bottom of the plates with a square shoulder for the lower edge of the plate to rest on. A piece of the top of the post in the centre is taken out one and a half inches inward three and a half inches down for the edge of the wheel to play there. The lower edge of the plate is four and a half inches from the top to the lid. The wheel is joined of a single board and is a segment of nearly one tenth of a circle of six inches diameter. The thickness of the wheel is one inch two semicircular grooves of suitable size for a cord, a fourth of an inch diameter are cut in the edge of the wheel round the circular part. Three handles are attached to the wheel to work it by one in the centre of the straight low

and must each come where the circle and straight line join.
A shaft one and $\frac{3}{4}$ inch diameter passing ^{thru} the centre of the wheel
pins, on the ends of which rest on the top edge of the plate.

A cap seven inches long and $2\frac{1}{2}$ inches wide cut in form of an astrol-
abe is fastened to the top edge of the plate by two screws for the pur-
pose of preventing the pin, from rising up when the machine is
in operation. The wheel is put in motion by the hand & the mo-
tion communicated to the shaft by a single cord.

The manner of attaching the cord to the wheel and pulleys is as follows.
One end of the cord is fastened to the handle in the centre of the top
edge of the wheel, it passes along the edge to where the cord comes
down, and is laid in the groove near the face of the wheel toward
the pulley, it continues in the groove past one pulley and the farthest
side of the other, how it passes from the wheel to the pulley one
and a half round it leaving the pulley on the side furthest from
the wheel it passes in a direction opposite to its direction on the
wheel to the ^{top} pulley, round which it passes, one and a half, then into
the other groove in the wheel where it continues in the former direction
to the opposite corner of the wheel from where it first entered the
groove, here the other end of the cord is fastened.

The handle to which the first end of the cord is fastened is, made
to turn in order to tighten the cord when necessary. The line of
the face of the wheel when hung must not be exactly parallel to
the side of the churn but turned a little diagonally about three eigh-
ths of an inch in 20 inches. This is necessary in order to bring the edge of
the groove, over the edge of one of the pulleys, and the edge of the other
from over the edge of the other pulley, so that the cord may pass from
the wheel to the first pulley, and from the other pulley to the wheel again
without friction moving one of the pins, or guides, on which the wheel
runs, three sixteenths of an inch toward one end of the churn will
accomplish this. That which I claim in the above described machine
is particularly new and of great value is the manner of applying the cord
to the pulleys, for the purpose of churning.
